AIR DISTRIBUTING DUCT

William Goodwin Richardson, Westwood, Mass.

Application July 7, 1944, Serial No. 543,937

3 Claims. (Cl. 98—40)

This invention relates to ventilating and air conditioning systems and relates more particularly to the distribution of air from such systems.

This invention provides an air distributing duct which may be in the form of an oversized mop board or base board which will extend around the sides of a room, and distribute air into the room from a plurality of points. The duct may be used at the floor of the room for distributing heated air; or used as a ceiling molding for distributing chilled air. Such ducts are particularly suitable for older type buildings where it is difficult to conceal duct work.

A feature of this invention resides in providing in such a duct, an inner chamber into which the conditioned air is supplied under pressure, the inner chamber having a wall containing a large plurality of relatively small perforations which discharge the air at a relatively high velocity into an outer chamber. The air expands in this outer chamber and is discharged through relatively large apertures and at a relatively low velocity into the room.

Objects of the invention are to distribute air uniformly and at low velocity into a room, and to accomplish this with a decorative duct which can readily be applied around the sides of a room to be supplied with conditioned air.

The invention will now be described with reference to the drawing, of which:

Fig. 1 is a side elevation, partially in section of a duct embodying this invention and formed as a base board around the sides of a room, and

Fig. 2 is a diagrammatic plan view of a room utilizing the duct of Fig. 1, and illustrates the air supply to and the distribution from, the duct.

The duct has the back wall 5 which is adapted to be placed against the inner surface of a vertical wall of the room. The wall 6 having the perforations 7, is arranged parallel to the wall 5 and spaced therefrom and has the horizontal upper portion 8 which contacts and is attached to the wall 5.

The walls 5 and 6 form an inner chamber 9 which is connected by the supply duct 10 with a conventional ventilating, heating or air conditioning system which is not illustrated and which is of the type which supplies air under substantial static pressure through the duct 10 into the passage 9.

The decorative outer wall 11 has the curved upper portion 12 which is attached to the upper end of the wall 5, the lower portion of the wall 11 being spaced from and extending parallel to the perforated wall 6. The horizontal lower portion 55

16 of the wall 12 interconnects the walls 11 and 6 and forms therebetween the outer expansion chamber 13.

The wall 11 has the closely spaced outlets 14 adjacent and extending parallel to the floor of the room, and has the upper outlets 15 adjacent the sides of the room and discharging air parallel thereto.

The above described duct preferably extends around the four sides of the room, being continuous except for door passages.

As illustrated by Fig. 2, there may be two oppositely disposed supply ducts 10. One or more than two ducts 10 may be provided.

15 In operation, the duct 10 supplies air under pressure into the inner chamber 9. Due to the small outlets 7, a uniform static pressure is built up in all portions of the inner chamber 9. The air issues from the apertures 7 at a relatively high 20 velocity which may, for example, be 3,000 feet per minute.

The discharge outlets 14 and 15 have total areas substantially larger than the total areas of the apertures 7 whereby the air is discharged into the 25 room at a relatively low velocity which may, for example, be 500 feet per minute.

The use of the double plenum chamber in the duct thus provides uniform distribution all around the room, yet with low velocity discharge 30 into the room.

The wall 11 may be of wood or of metal treated to imitate wood so as to blend artistically with the room interior.

The above-described features could, of course, 35 be included in a duct adjacent the ceiling of the room as probably would be preferred for distributing chilled air. Ducts embodying the invention thus could be used adjacent the floor of the room for distributing heated air, and adjacent the ceiling 40 of the room for distributing chilled air.

While one embodiment of the invention has been described for the purpose of illustration, it should be understood that the invention is not limited to the exact apparatus illustrated as modifications thereof may be suggested by those skilled in the art without departure from the essence of the invention.

What is claimed is:

1. An air distributing duct for placement 50 against, and for extension along, the vertical side of a room, comprising a relatively long, a relatively high and a relatively narrow casing having a base for placement on the floor of said room, an inner wall extending substantially vertically from said base, and a partition in said casing

having a substantially vertical portion spaced from said wall and having an upper portion connecting with said wall below the upper end thereof, said partition dividing said casing into inner and outer chambers, the upper portion of said outer chamber extending over said inner chamber, said partition having a plurality of relatively small apertures therein, said casing having an inlet in said base thereof for connecting said inner chamber to an air supply duct, the outer wall of said casing having a plurality of outlets therein above said upper portion of said partition, the area of said outlets being substantially greater than the area of said apertures whereby the air from said outer chamber is discharged upwardly above said inner chamber into the room at a velocity substantially less than the air is discharged through said apertures from said inner chamber into said outer chamber.

2. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having an inlet in the base thereof for connecting said inner chamber to an air supply duct, means forming an air outlet in the outer wall of said casing for directing air from said outer chamber along substantially vertical lines, and means forming an air outlet in said outer wall of said casing for

3. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having

5 directing air from said outer chamber along substantially horizontal lines, the area of said outlets being substantially greater than the area of said apertures whereby the air from said outer chamber is discharged into the room at a velocity substantially less than the air is discharged through said apertures from said inner chamber into said outer chamber.

10 3. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having

15 3. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having

20 3. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having

25 3. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having

30 3. An air distributing duct for placement against, and for extension along, the side of a room, comprising a relatively long, a relatively high and a relatively narrow casing having a substantially vertical inner wall, a partition in said casing having a substantially vertical portion spaced from said wall and having an upper portion connecting with said wall, said partition dividing said casing into inner and outer chambers, said partition having a plurality of relatively small apertures therein, said casing having
